(57) **CLAIM**

The ornamental design for a display panel or screen with a graphical user interface, as shown and described.

DESCRIPTION

FIG. 1 is a front view of a display panel or screen with a graphical user interface showing our new design;

FIG. 2 is a second embodiment thereof;

FIG. 3 is a third embodiment thereof;

FIG. 4 is a fourth embodiment thereof;

FIG. 5 is a fifth embodiment thereof;

FIG. 6 is a sixth embodiment thereof;

FIG. 7 is a seventh embodiment thereof; and,

FIG. 8 is an eight embodiment thereof.

The outermost broken line rectangle illustrates a display panel or screen. The remaining broken lines, including all text, illustrate portions of the graphical user interface. None of the broken lines form part of the claimed design.
